COMPRESSOR

Johann Heinrich, Berlin-Tegel, Germany, assignor to Rheinmetall-Borsig Aktiengesellschaft Werk Borsig, Berlin-Tegel, Berlin-Tegel, Germany, a corporation of Germany

Application May 25, 1938, Serial No. 209,939
In Germany July 12, 1937

8 Claims. (Cl. 230—31)

This invention relates to compressors and refers more particularly to devices for regulating gradually and without steps the amount of the medium compressed by compressors the suction valves of which are carried by their pistons.

In compressors of a different type wherein the suction valves are situated upon the side walls or the cover of the main cylinder, the regulation of the amount of the compressed medium may be carried out by keeping the suction valve open during a part of the compression stroke; then a portion of the medium is removed through the suction valve while only a predetermined amount of the medium is compressed by the main piston of the compressor. The opening and closing of the suction valve is caused by an auxiliary piston which is movable within an auxiliary cylinder and which may be actuated by the medium which has been compressed during the previous compression stroke. The medium which exerts its pressure upon the auxiliary piston can return gradually to the cylinder by means of a by-pass with the result that the pressure upon the auxiliary piston drops gradually until it becomes smaller than the pressure exerted upon the suction valve by the medium situated within the main cylinder of the compressor during the following compression stroke. This causes the closing of the suction valve. Then the medium remaining in the main cylinder is compressed to the final pressure.

This procedure cannot be used in compressors the suction valves of which are carried by the main pistons and wherein the medium flows in the same direction through the main cylinder from the suction valve to the outflow valve carried by the cover of the cylinder, since suction valves of this type cannot be operated in the described manner.

An object of the present invention is to adapt the described procedure to so-called uniform flow compressors, used particularly in refrigerating plants, a characteristic feature of which is the arrangement of the suction valves upon the main pistons.

Another object is the provision of means which regulate the amount of the medium compressed by a uniform flow compressor in such manner that the gaseous cooling medium removed from the evaporator is not heated excessively when it is introduced into the main cylinder, thereby avoiding a drop in the efficiency of the compressor.

A further object is the provision of means for

regulating the amount of the compressed medium in cooling plants in conformity with the desired output of the evaporator.

Other objects of the present invention will be apparent in the course of the following specification.

The objects of the present invention may be realized through the provision of an auxiliary valve which is carried by the side walls of the cylinder close to its cover and which is connected with an auxiliary circuit provided with a regulating valve. The amount of the medium compressed by the compressor depends upon the moment of closing of the auxiliary valve which is determined by the adjustment of the regulating valve. When the auxiliary valve is open, it connects the interior of the main cylinder with a chamber which is provided in the casing of the main cylinder and which is in communication with the main suction conduit.

The auxiliary valve is so located that it is not covered by the main piston in the upper dead end position of the latter, since otherwise it would not be possible to regulate the compressor when it is running without performing any substantial useful work.

The invention will appear more clearly from the following detailed description when taken in connection with the accompanying drawings, showing by way of example preferred embodiments of the inventive idea.

In the drawings:

Figure 1 is a vertical section through a uniform flow compressor constructed in accordance with the principles of the present invention;

Figure 2 is a section through a compressor of a somewhat different type; and

Figure 3 is a section along the line III—III of Figure 2.

The compressor shown in Figure 1 of the drawings is of the vertical uniform-flow type and is provided with a main cylinder 1, which encloses a main piston 2. The piston 2 carries a suction valve 3 provided with a spring 50. The compressed medium is removed through an outflow valve 4, which is provided with a spring 51 and which is situated close to the cover 55 of the cylinder 1.

The medium to be compressed is introduced into the cylinder through a passage or suction conduit 52 which is in communication with an annular suction chamber 13. The compressed medium flows through the openings 58 of the valve 4 into a chamber 53 and is removed through the passage 54.

In accordance with the present invention, the compressor is provided with an auxiliary valve 5, which is situated close to the cover 55 of the cylinder 1 and is connected by a rod 56 with an auxiliary piston 6, which is reciprocable within an auxiliary cylinder 7. The valve 5 is adapted to interrupt the connection between the interior of the cylinder 1 and a return-flow chamber 15 which is in communication with the suction chamber 13.

One end of a conduit 8 is in communication with the interior of the cylinder 1 directly underneath the valve 4. The other end of the conduit 8 is in communication with the interior of the auxiliary cylinder 7. The conduit 8 carries a non-return valve 9, which is situated intermediate its ends. An auxiliary conduit 10, which carries a manually adjustable throttle valve 12, is in communication with the conduit 8 on both sides of the non-return valve 9.

The device operates as follows:

During the compression stroke of the piston 2, a part of the compressed medium flows through the conduit 8 and through the non-return valve 9 into the auxiliary cylinder 7. Although this compressed medium will exert a pressure upon the auxiliary piston 6, it will not be able to open the valve 5 at that time, since the pressure of the compressed medium acting upon the larger surface of the valve 5 will be greater than that exerted upon the piston 6.

In the course of the following suction stroke, the pressure will drop within the main cylinder 1. Although the compressed medium within the cylinder 7 will not be able to return through the non-return valve 9, it will be able to flow around the valve 9 through the auxiliary conduit 10 which is provided with the throttle valve 12. The amount of the returning compressed medium, and therefore the rate of the drop in pressure within the auxiliary cylinder 7, can be easily regulated by adjusting by hand the throttle valve 12.

In view of the drop in pressure within the main cylinder 1, the compressed medium remaining in the cylinder 1 will move the piston 6 and open the valve 5.

When the piston 2 has completed its suction stroke and begins its next compression stroke, the valve 5 will remain open for a predetermined period of time until the increase in pressure within the cylinder 1 will cause the closing of the valve 5.

While the valve 5 remains open, a portion of the medium within the cylinder 1 flows through the passage 57 of the valve 5 into the chamber 15 of the cylinder 1. After the closing of the valve 5, which is due to the increase in pressure within the cylinder 1, the medium remaining within the cylinder is compressed to its final pressure and causes the outflow valve 4 to open. Then the compressed medium flows through the passages 58 of the valve 4 into the chamber 53 and is removed through the conduit 54.

While the valve 5 remains open, the medium flowing through the passage 57 into the chamber 15, passes into the suction chamber 13, so that it can return to the interior of the cylinder 1 during the next suction stroke of the piston.

The compressor illustrated in Figure 2 is provided with a main piston 59, which carries a suction valve 26. A separate auxiliary valve 25 is situated adjacent the cover of the compressor. The piston 59 is reciprocated within the main cylinder 60 and is connected by the rod 61 with the main shaft 30.

The auxiliary valve 25 is connected by a connecting rod 62 with a piston 27 which is reciprocated within the auxiliary cylinder 43. The piston 27 cooperates with the spring 44 which surrounds a portion of the rod 62.

The shaft 30 is carried by the main casing 28 of the compressor.

The main cylinder 60 is provided with an outflow valve 63 and an outflow chamber 38. One end of the pipe 39 is connected with the chamber 38 while the opposite end of this pipe is in communication with an opening 64 formed in a cover 65.

The cover 65 is connected to a separate casing 29 which constitutes a bearing for that end of the shaft 30 which is used for regulating purposes. The casing 29 is connected to the main casing 28. The casing 29 is provided with an opening 41 which is in communication with one end of a pipe 42. The opposite end of the pipe 42 is in communication with the interior of the auxiliary cylinder 43.

A branch pipe 46 which carries a throttle valve 47 connects the pipe 42 with a chamber 43 provided in the cylinder 60. Due to this arrangement, the moment of the closing of the auxiliary valve 25 depends upon the time required for the flow of the compressed medium from the auxiliary cylinder 43 and through the throttle valve 47. The returning compressed medium is conducted through the return-flow chamber 45 directly to the suction chamber 49 of the compressor.

This compressor is provided with a rotary sliding device for regulating the time of the closing of the auxiliary valve 25. Devices of this type are described in greater detail in the co-pending patent application, Serial No. 209,938, filed May 25, 1938, for Compressors.

As shown in Figure 3, the shaft 30 is provided with an axial passage 31, one end of which is connected with a radial passage or bore-hole 32 extending at right angles to the passage 31. A regulating sleeve 34 encloses this portion of the shaft 30 and is carried by the casing 29.

The space 66 between the shaft 30 and the inner walls of the casing 29 is longer than the sleeve 34, so that the sleeve 34 may be moved axially within the space 66. The movement of the sleeve 34 is carried out by means of the spindle 35 and the arms 36 which engage the outer surfaces of the sleeve 34. The spindle 35 is carried by the cover 65.

The operation of the device is as follows:

A portion of the compressed fluid within the chamber 38 flows through the pipe 39 into the chamber 40 enclosed by the cover 65 and fills the passage 31 and 32 formed in the shaft 30. In the position illustrated in Figure 3, the sleeve 34 interrupts the connection between the passage 32 and the opening 41.

When the sleeve 34 is so shifted by means of the spindle 35 that its opening 37 establishes a communication between the passage 32 formed in the shaft 30 and the passage 41 formed in the casing 29, then the compressed medium contained in the chamber 40 will flow through the passages 31 and 32 of the shaft 30, the opening 37 of the sleeve 34, and the passage 41 of the casing 29, reaching the pipe 42 and the interior of the auxiliary cylinder 43.

The compressed medium within the cylinder 43 will move the piston 27 thereby compressing the spring 44 and opening the valve 25 to establish a connection between the interior of the cylinder 60 and the chamber 45.

The auxiliary valve 25 is so located that it remains above the piston 59 in the upper dead-end position of the piston, since otherwise it would be impossible to regulate the compressor when it is running without performing any substantial useful work.

The compressed medium situated within the auxiliary cylinder 43 will gradually return through the passage 46 into the chamber 45 until the auxiliary valve 25 is closed by the increased pressure within the cylinder 60 in the course of the following compression stroke of the piston 59.

In the position shown in Figures 2 and 3 no connection is established between the pipes 39 and 42, so that the valve 25 does not open at all and the compressor is operated at full capacity.

If it is desired to reduce the amount of the medium compressed by the compressor, then the spindle 35 is actuated to shift the sleeve 34 axially until the opening 37 in the sleeve 34 is placed between the opening 41 which is in communication with the pipe 42, and the passage 32 within the shaft 30.

In the described construction, the compressed medium which has been removed already from the interior of the main cylinder 60 is introduced into the chamber 38 and the pipe 39.

Obviously, the pressure medium used for operating the piston 27 can be taken from a separate container of a compressor plant or from any other suitable source. The advantage of thus regulating the auxiliary valve 25 is that it is possible to further diminish and to regulate exactly the amount of the medium compressed by the compressor.

In order to retain the advantages of a uniform flow compressor, it is necessary that the auxiliary valve be open only at the beginning of each compression stroke and that it be closed during each suction stroke. This can be attained by making the spring 44 actuating the auxiliary valve 25, stronger than the spring 70 actuating the suction valve 26.

It was found that when the compressed medium is removed directly from the main cylinder, if the amount to be compressed is comparatively small, the conduits and chambers of the device are insufficiently filled with the compressed medium and the rate of the drop in pressure in the auxiliary cylinder is comparatively small, so that a comparatively long time is required to diminish that pressure to the desired extent. Since the curves representing the drop in pressure in the auxiliary cylinder 43 and the pressure acting upon the valve 25 are comparatively flat, their point of intersection, which determines the moment of the closing of the auxiliary valve, cannot be determined exactly, as is explained in greater detail in the aforesaid co-bending patent application. This drawback which is particularly noticeable in the case of refrigeration plants, wherein the amount of the compressed medium determines the output, is eliminated by the described construction.

It is apparent that the specific illustrations shown above have been given by way of illustration and not by way of limitation, and that the structures above described are subject to wide variation and modification without departing from the scope or intent of the invention, all of which variations and modifications are to be included within the scope of the present invention.

What is claimed is:

1. A regulating device for a compressor having

a cylinder, a main piston reciprocable within said cylinder, and a suction valve carried by said piston; said regulating device comprising a separate auxiliary valve carried by said cylinder, and means connected with said auxiliary valve for maintaining it open during a part of the compression stroke of the main piston.

2. A regulating device for a compressor having a cylinder, a main piston reciprocable within said cylinder, and a suction valve carried by said piston; said regulating device comprising a separate auxiliary valve carried by said cylinder, and being situated above said piston in the course of the reciprocation of the latter, and means connected with said auxiliary valve for maintaining it open during a part of the compression stroke of the main piston.

3. A regulating device for a compressor having a cylinder, a main piston reciprocable within said cylinder, and a suction valve carried by said piston; said regulating device comprising a separate auxiliary valve carried by said cylinder, means supplying a pressure medium to said auxiliary valve to maintain it open during a predetermined period of time, and means connected with the first-mentioned means to regulate the pressure of said compressed medium upon said auxiliary valve, whereby the period of time during which said auxiliary valve remains open is varied.

4. A regulating device for a compressor having a cylinder, a main piston reciprocable within said cylinder, a suction chamber being formed in said cylinder, and a suction valve carried by said piston; said regulating device comprising an auxiliary valve carried by said cylinder, means constituting a part of said cylinder and forming a return-flow chamber which is in communication with said suction chamber, and means connected with said auxiliary valve for maintaining it open during a part of the compression stroke of the main piston, a portion of the medium flowing from the interior of said cylinder to said return-flow chamber and said suction chamber.

5. A regulating device for a compressor having a cylinder, a main piston reciprocable within said cylinder, a suction valve carried by said piston, and a spring for closing said suction valve; said regulating device comprising a separate auxiliary valve carried by said cylinder, a spring for closing said auxiliary valve, the last-mentioned spring being stronger than the first-mentioned spring, and means connected with said auxiliary valve for maintaining it open during a predetermined period of time.

6. A regulating device for a compressor having a cylinder, a main piston reciprocable within said cylinder, and a suction valve carried by said piston; said regulating device comprising an auxiliary valve carried by said cylinder, an auxiliary cylinder constituting a portion of the first-mentioned cylinder, an auxiliary piston connected with said auxiliary valve and reciprocable within the auxiliary cylinder, means connected with two cylinders for supplying the medium compressed by the first-mentioned cylinder to the auxiliary piston, and regulatable means connected with the first-mentioned means for gradually reducing the pressure of the compressed medium upon the auxiliary piston.

7. A regulating device for a compressor having a cylinder, a main piston reciprocable within said cylinder, and a suction valve carried by said piston; said regulating device comprising an auxiliary valve carried by said cylinder, an auxiliary

5 cylinder constituting a portion of the first-mentioned cylinder, an auxiliary piston connected with said auxiliary valve and reciprocable within the auxiliary cylinder, conduits connected with the two cylinders for supplying the medium compressed by the first-mentioned cylinder to the auxiliary piston, another conduit connected with one of the first-mentioned conduits and said cylinder and communicating with said suction 10 chamber for gradually removing the compressed medium from the auxiliary cylinder to the suction chamber, and a throttle valve carried by the last-mentioned conduit.

15 8. A regulating device for a compressor having a cylinder, a main piston reciprocable within said cylinder, and a suction valve carried by said piston; said regulating device comprising an aux-

iliary valve carried by said cylinder, an auxiliary cylinder constituting a portion of the first-mentioned cylinder, an auxiliary piston connected with said auxiliary valve and reciprocable within the auxiliary cylinder, a conduit having one end 5 communicating with the interior of the first-mentioned cylinder and another end communicating with the interior of the auxiliary cylinder to supply the medium compressed by the first-mentioned cylinder to the auxiliary piston, a non-return valve carried by said conduit, an auxiliary conduit communicating with the first-mentioned conduit on both sides of the non-return valve, and a throttle valve carried by the auxiliary conduit. 10

15 JOHANN HEINRICH.
